Seward, both of Los Angeles, Calif.

Application February 12, 1936, Serial No. 63,562

10 Claims. (Cl. 123—117)

Our invention relates to a circuit breaker for the spark distributors of the ignition circuits of internal combustion engines and the construction herein disclosed is an improvement on the subject 5 matter of our copending application for U. S. Letters Patent filed October 7, 1935, Serial No. 43,814 Patent No. 2,066,640 dated January 5, 1937.

In our co-pending application, the position of 10 the breaker arm with respect to the timing cam is controlled by a shaft or rod mounted for rocking movement and movable lengthwise by means of a pin that traverses an inclined slot in the sleeve that surrounds the rod or shaft and it is the principal object of our present invention to eliminate the parts just mentioned and accomplish the same results by mounting the breaker arm on a rotary member that is arranged for movement on an axis that is offset or eccentric with respect to 15 the axis of the timing cam, thus materially reducing the number of operating parts of the device and providing a construction that is relatively simple and practical, inexpensive of manufacture and positive in operation.

20 A further object of our invention is, to provide simple and efficient means for automatically regulating the time period of electrical dwell or contact of the breaker contacts and thereby regulating the periods of saturation of the coil in 25 the primary circuit to correspond with the speed of the gaseous fuel mixture passing through the carburetor of the internal combustion engine, with which the device is associated and the demands of the coil for a constant millampere output.

In connection with the ignition systems of internal combustion engines, it will be understood that while the engine is running at low or idle speeds, a relatively short contact in the primary circuit produces sufficient saturation of the coil without oversaturation and that while the engine is running at high speeds, a longer contact is necessary to properly saturate the coil. Over-saturation heats and burns out the coil and the contact points in the distributor head and these objectionable results are eliminated where my improved circuit breaker is used.

It is the magnetizing and demagnetizing of the 50 core of the coil that induces the secondary current into the secondary winding and it is the primary current flowing through the primary winding and around the core of the coil that magnetizes the core. Thus the core is magnetized 55 when the circuit is closed and demagnetized when

the circuit is open. The spark for igniting the gaseous fuel charges occurs when the coil is demagnetized by opening the primary circuit.

To produce a strong spark, the core of the coil must be completely saturated or magnetized and 5 in order to do this, the primary circuit must be closed by the contact points for a sufficient length of time by reason of the fact that the coil will not become magnetized instantaneously. A certain period of time is required. This being true, 10 it will be seen that the spark or secondary current will grow weaker as the speed of the engine increases because the speed of the cam that operates the circuit breaker correspondingly increases, which shortens the time of contact or 15 dwell of the contact points of the primary circuit.

It is one of the purposes of our invention, to provide simple and efficient means that is automatically actuated, preferably by the velocity of 20 the flow of gaseous mixture through the carburetor into the intake manifold, for controlling the periods of contact or the time of dwell of the contacts in the primary circuit, corresponding with the engine speeds, in order to bring about 25 the proper timing of the saturation of the core of the coil.

With the foregoing and other objects in view our invention consists in certain novel features of construction and arrangements of parts that 30 will be hereinafter more fully described and claimed and illustrated in the accompanying drawing in which:

Fig. 1 is a top plan view of a circuit breaker and spark distributor constructed in accordance with our invention and showing in section the 35 vacuum actuated means that is connected to the carburetor and which automatically moves the eccentrically mounted member that carries the breaker arm.

Fig. 2 is a plan view of the circuit breaker and 40 spark distributor and showing the movable parts thereof in shifted position.

Fig. 3 is a cross section taken on the line 3—3 of Fig. 1.

Fig. 4 is a plan view of the eccentrically mounted 45 breaker arm carrying plate and the disc or plate upon which the same is mounted.

Referring by numerals to the accompanying drawing which illustrates a preferred embodiment of our invention, 10 designates a conventional distributor head in which is mounted for rotation the usual axially disposed shaft 11 carrying the timing cam 12.

Suitably secured within the recessed upper por- 55

tion of head 10 is a disc or plate 13 and the central portion of this disc or plate is pressed downwardly to form an eccentrically arranged circular recess 14.

5 An inwardly presented flange 15 surrounds the lower portion of this recess.

Mounted on flange 15, and secured against rotation, is the outer race 16 of a conventional anti-friction bearing, which latter includes a rotatably 10 mounted inner race 17 and a series of balls 18 disposed between the races.

Disposed above this antifriction bearing, is a plate or disc 19 provided with a centrally arranged opening and surrounding the latter, is a 15 depending flange 20 that is carried by the inner race 17. As a result of this construction and particularly the provision of the eccentric recess 14, the antifriction bearing and the depending flange 20 of plate 19 are eccentrically arranged with respect to the axis of shaft 11 that carries the timing cam 12.

Pivotedly mounted in the conventional manner on plate 13, is a breaker arm 21 of the usual construction and which carries at its free end a 25 contact point 22.

Carried by the intermediate portion of the breaker arm 21, is a block or shoe 23 that is adapted to be engaged by the high points of the timing cam 12.

30 Contact 22 is adapted to engage a fixed contact 24, the latter being carried by a screw 25 that is seated in a bracket 26 and which screw is secured in its adjusted position by means of a lock nut 27. Bracket 26 is carried by plate 13.

35 Pivotedly connected to plate 13 adjacent the pivoted end of the breaker arm 21, is one end of a link 28, the same extending substantially tangential from said plate through a housing 29 that is connected to the breaker head 10 and the outer 40 end of this link is pivotally connected to the center of a diaphragm 30. The edge of this diaphragm is clamped between the divided parts of a housing 31 and one of the parts of said housing having a tubular extension 32. The outer end 45 of this extension 32 is closed and extending through said closed end and communicating with the chamber in the extension 32 is a tubular duct 33 that leads to the chamber within a conventional carburetor 34, preferably at a point between the throttle valve T and the venturi V.

50 Interposed between the central portion of diaphragm 30 and the outer end of the tubular member 32, is an expansive coil spring 35, which yieldingly resists the movement of the diaphragm toward the side of the housing 31 having the tubular extension 32.

That portion of tube 33 that extends into the carburetor functions as a Pitot tube to control the pressure exerted on the diaphragm 30. In some 60 instances, to produce the desired results, tube 33 may be extended directly into the venturi or into the carburetor at or near the point of highest velocity flow of the gaseous mixture therethrough.

When the internal combustion engine with 65 which our improved circuit breaker is associated, is operating at idle speed, the velocity of the gaseous mixture passing through the carburetor is not strong enough to overcome the tension of spring 35 and the diaphragm 30. Hence the latter occupies its normal position as illustrated in Fig. 1.

Under such conditions plate or disc 15 supported on the antifriction bearings in the eccentric recess 14 in disc 13, occupies a position so that 70 when contact 22 carried by the free end of said

breaker arm is in engagement with adjustable contact 24, the face of shoe 23 is spaced a very slight distance away from the central portion of one of the angular faces of cam 12.

Under such conditions the time period of engagement between the contacts 22 and 24 is comparatively short, but even so such comparatively short dwell of the contacts is sufficient to permit the flow of sufficient current through the contact and other connections to bring about the desired 10 degree of saturation of the coil.

As the cam 12 moves a short distance, one of the faces thereof will engage shoe 23 and as a result of such engagement breaker arm 21 will be swung outwardly away from the cam, thus separating the contacts 22 and 24 and the flow of current to the coil ceases.

Thus under slow or idling speed there is a relatively short period of dwell or contact between the contacts 22 and 24 and a much longer time 20 period of separation between such contacts and as a result the coil is saturated for only a short time or while the contacts 22 and 24 are closed.

As the throttle is opened to increase the speed of the engine, the corresponding increase in the 25 velocity of the gaseous fuel mixture from the carburetor to the intake manifold produces suction through tube 33 and this suction is exerted upon diaphragm 30 to draw the same toward the side of housing 31 having the extension 32 and 30 the movement thus imparted to said diaphragm is imparted by link 28 to the disc or plate 13, such movement causing partial rotation of said disc or plate in the eccentric recess 14.

Due to the fact that plate 13 carrying the breaker arm 31 is eccentrically mounted with respect to the axis of the cam 12, the breaker arm will be carried into a position whereby the face of contact shoe 23 occupies a position a greater distance away from the axis of the shaft carrying the cam with the result that the high portions of the cam only engage the face of shoe 23 for shorter periods of time than under the conditions previously described while the engine is idling and such action increases or lengthens the dwell or periods 45 of contact between the contacts 22 and 24, thus correspondingly lengthening the time periods of saturation of the coil and which result is desirable for higher engine speeds.

Thus when the engine is run at its maximum 50 or highest speed, the dwell or time period of contact between the contacts 22 and 24 are of longest duration and this brings about the desired degree of saturation of the coil with the contact point.

As the speed of the engine decreases its idling speed, the suction produced through the carburetor correspondingly decreases and diaphragm 30 returns to its normal position so as to partially rotate plate 33 on the eccentrically 60 arranged bearing 16, thus shifting the position of the breaker arm and particularly the contact shoe 23 with respect to the axis of the cam and the periods of dwell or contact between the contacts 22 and 24 will be correspondingly increased 65 so as to bring about the desired degree of saturation of the coil during the decreasing and idle speed of the engine.

Thus it will be seen that in our improved circuit breaker, the mounting of the contact arm on a rotary member having an axis offset or eccentric with respect to the axis of the shaft carrying the cam provides simple and efficient means for increasing or decreasing the gap in the ignition circuit according to the speed of the en- 75

gine and the demands of the coil for a constant milliampere output and the velocity of the gaseous mixture flowing from the carburetor to the intake manifold automatically controlling the position of the breaker arm and the contact shoe carried thereby relative to the cam that operates said breaker arm.

The use of our improved circuit breaker enables a higher voltage coil to be used in the ignition system and such condition is especially desirable and advantageous inasmuch as it produces the desired results, particularly at high engine speeds.

Our improved form of circuit breaker may be advantageously employed in connection with the present forms of automatic timers and ignition devices by merely substituting our improved form of breaker arm carrying ring or plate and its supporting plate, for the corresponding parts now utilized in standard forms of circuit breakers and spark distributors.

The eccentrically mounted plate that carries the breaker arm is mounted so that when the engine speeds up so as to impart movement to said plate, such movement is in the opposite direction from that of the rotary movement of the shaft carrying the cam and as a result of this movement, the spark is automatically advanced and such advance is proportionate or in keeping with the engine speed.

As illustrated by the arrow and legend ADV. in Fig. 1, the rotary movement of the plate 19 when actuated as a result of increased engine speed, is anti-clockwise and at all times the shaft 35 11, carrying timing cam 12, rotates clockwise as indicated by the arrows Figs. 1 and 2. When the engine speed decreases, the rotary movement of the plate 19 is clockwise as indicated by the arrow and legend RET. in Fig. 2.

Obviously as the breaker arm carrying plate returns to its normal position it moves in the same direction with that of the cam and the spark is correspondingly retarded as the engine slows down.

In order to regulate the tension of spring 35, a rod 36 is screw-seated in the fitting that connects tube 33 to the tubular extension 32 of the diaphragm housing 31, and the inner end of this screw rod carries a disk 37 that provides 50 a bearing for the adjacent end of spring 35. Thus the action of the diaphragm may be readily controlled.

As a result of our improved construction, it is not necessary to employ the conventional weights utilized in connection with the shaft of the timing cam for advancing the spark, but if it is desired to use the eccentrically mounted plate in connection with distributor heads already equipped with the weights that control the position 60 of the cam and the consequent timing of the spark, then the breaker arm carrying plate is mounted so that the distance between its axis and the axis of the cam is increased and thus only a relatively short rotary movement imparted to the eccentrically mounted plate plus the action of the weights associated with the cam is sufficient to change the position of the breaker arm so as to vary the period of dwell between the contact points and also to bring about the 65 desired advance or retarding of the spark resulting from engagement of the contacts 22 and 24.

A further advantage gained by our improved construction is smoothness of running the engine at idle speeds with the use of greater advanced spark due to the correct period of dwell of con-

tact to bring about the proper degree of coil saturation.

Thus it will be seen that we have provided a circuit breaker for spark distributors that is relatively simple in construction, inexpensive of manufacture and very effective in performing the functions for which it is intended.

It will be understood that minor changes in the size, form and construction of the various parts of our improved circuit breaker for spark distributors may be made and substituted for those herein shown and described without departing from the spirit of the invention, the scope of which is set forth in the appended claims.

We claim as our invention:

1. In a circuit breaker for spark distributors including a cam, a contact carrying breaker arm and a relatively fixed contact, a member mounted for rotary movement on an axis that is eccentric relative to the axis of the cam, said rotary member carrying said breaker arm and said relatively fixed contact and automatically operating means controlled by the velocity flow of the gas air mixture through the carburetor with which the circuit breaker is associated for imparting movement to said rotatably mounted member.

2. In a circuit breaker for spark distributors including a rotary cam, a member mounted for rotary movement on an axis that is eccentric to the axis of said cam, a contact carrying breaker arm pivotally mounted on said member, a relatively fixed contact carried by said member and automatically operating means controlled by the velocity flow of the gas air mixture through the carburetor with which the circuit breaker is associated for imparting movement to said member to change the position of said contact carrying breaker arm and the relatively fixed contact with respect to said cam.

3. In a circuit breaker for spark distributors including a rotary cam, a member mounted for rotary movement on an axis that is eccentric to the axis of the cam, a breaker arm pivotally mounted on said member, a shoe carried by said breaker arm, which shoe is adapted to be engaged by the cam during its rotary movement, a contact carried by said breaker arm, a relatively fixed contact mounted on said member and adapted to be engaged by the contact carried by the breaker arm and automatically operating means actuated and controlled by the velocity flow of the gas air mixture through the carburetor with which the circuit breaker is associated for imparting movement to said member so as to change the position of the parts carried thereby with respect to said cam.

4. In a circuit breaker for spark distributors including a rotary cam, of a member mounted for rotation adjacent said cam, the axis of which member is eccentric with respect to the axis of the cam, a breaker arm pivotally mounted on said rotatably mounted member, a shoe carried by said breaker arm, which shoe is adapted to be engaged by said cam, a contact carried by the breaker arm, a relatively fixed contact that is adapted to be engaged by the contact carried by said breaker arm, and automatically operating means actuated and controlled by the velocity flow of the gas air mixture through the carburetor with which the circuit breaker is associated for imparting rotary movement to said eccentrically arranged member.

5. In a circuit breaker for spark distributors

including a rotary cam, a member mounted for rotation adjacent said cam and having an axis that is eccentric with respect to the axis of said cam, a breaker arm pivotally mounted on said member, a shoe carried by said breaker arm with which said cam is adapted to engage, a contact carried by said breaker arm, a relatively fixed contact carried by said member with which the contact carried by the breaker arm is adapted 10 to engage and means actuated and controlled by the velocity of the gas-air mixture through the carburetor with which the circuit breaker is associated for imparting movement to said member to change the positions of the parts 15 carried thereby with respect to the cam so as to increase or decrease the periods of contact or dwell between the contact carried by the breaker arm and the relatively stationary contact.

6. In a circuit breaker for spark distributors 20 including a rotary cam, a member mounted for rotation adjacent said cam and having an axis that is eccentric with respect to the axis of said cam, a breaker arm pivotally mounted on said member, a shoe carried by said breaker arm with 25 which said cam is adapted to engage, a contact carried by said breaker arm, a relatively fixed contact carried by said member with which the contact carried by the breaker arm is adapted to engage and means controlled by the speed 30 of the engine with which the circuit breaker is associated for imparting movement to said member to change the positions of the parts carried thereby with respect to the cam so as to increase or decrease the periods of contact or dwell be- 35 tween the contact carried by the breaker arm and the relatively stationary contact.

7. The combination with a spark distributor 40 head and the rotary cam associated therewith, of a member mounted for rotation on said head and having an axis that is eccentric relative to the axis of said cam, a breaker arm pivotally mounted on said member, a shoe carried by said breaker arm and adapted to be engaged by said cam, a contact carried by said breaker arm, a relatively fixed contact carried by said member and adapted to be engaged by the contact carried by the breaker arm and means actuated and controlled by the flow of gas-air mixture through 45 the carburetor with which the distributor head is associated for imparting movement to said member to change the position thereof and the

positions of the parts carried thereby with respect to said cam.

8. The combination with a spark distributor head and the rotary cam associated therewith, of a member mounted for rotary movement on 5 said head, the axis of which member is eccentric with respect to the axis of the cam, a breaker arm pivotally carried by said rotatably mounted member, a shoe carried by said breaker arm and adapted to be engaged by said cam, a contact 10 carried by said breaker arm, a relatively stationary contact carried by said member and adapted to be engaged by the contact carried by said breaker arm and automatically operating means actuated and controlled by the 15 velocity flow of the gas air mixture through the carburetor with which the spark distributor is associated for imparting movement to said eccentrically mounted member.

9. The combination with a spark distributor 20 head and the rotary cam associated therewith, of a member mounted for rotary movement on said head, the axis of which member is eccentric with respect to the axis of the cam, a breaker arm pivotally carried by said rotatably mounted 25 member, a shoe carried by said breaker arm and adapted to be engaged by said cam, a contact carried by said breaker arm, a relatively stationary contact carried by said member and adapted to be engaged by the contact carried by 30 said breaker arm and automatically operating means actuated and controlled by the speed of the engine with which the circuit breaker is associated for imparting rotary movement to said eccentrically mounted member.

10. In a circuit breaker for spark distributors, including a rotary cam, a member surrounding 35 said cam and mounted for rotation on an axis that is eccentric with respect to the axis of said cam, a breaker arm pivotally mounted on said 40 member, a shoe carried by said breaker arm with which said cam is adapted to engage, a contact carried by said breaker arm, a relatively fixed contact carried by said breaker arm with which the contact carried by the breaker arm is adapted 45 to engage, means located adjacent the distributor for converting vacuum suction into movement, and means connecting said converting means with the eccentrically mounted breaker arm carrying member.
